SERVICE STATION BUILDING OR THE LIKE

Albert M. Shotmeyer, 371 Sicomac Ave., Wyckoff, N.J.

Filed Sept. 9, 1959, Ser. No. 57,494

Term of patent 14 years

(Cl. D13—1)

Des. 190,629

PAGE 2

FIG 3

FIG 4

FIGURE 1 is a front elevation of my new design for a service station building or the like;

FIGURE 2 is a rear elevation thereof;

FIGURES 3 and 4 are side elevations, respectively, of the building; and

FIGURE 5 is a fragmentary top plan view of one end of the building.

For convenience of illustration only, the several views have been provided with shading to indicate portions of a conventional tile-like roof pattern, it being understood that the shading continues throughout the adjacent plain areas shown to complete the roof pattern. It is to be further understood that the portions of the building block-like and brick-like wall patterns shown in FIGURES 2 and 4, respectively, continue throughout the adjacent plain areas to complete the respective wall patterns of FIGURES 2 and 4.

I claim:

The ornamental design for a service station building or the like, substantially as shown and described.
